[57] CLAIM

The ornamental design for a pouch, substantially as shown and described.

DESCRIPTION

FIG. 1 is a perspective view of a pouch showing my new design in a partially opened condition;

FIG. 2 is a front elevational view thereof;

FIG. 3 is a top plan view thereof;

FIG. 4 is a bottom plan view thereof;

FIG. 5 is a side elevational view thereof, as seen from the left side thereof;

FIG. 6 is a side elevational view thereof, as seen from the right side thereof;

FIG. 7 is a rear elevational view thereof; and

FIG. 8 is a plan view showing the pouch in the fully opened condition, an intermediate portion being broken away and omitted for convenience of illustration.

FIG. 1

FIG. 2
